W. M. MYERS

WATER PURIFIER

Filed May 28, 1927

UNITED STATES PATENT OFFICE.

WILLIAM M. MYERS, OF ST. JOSEPH, MISSOURI, ASSIGNOR TO EARL H. RORABACK, OF KANSAS CITY, MISSOURI.

WATER PURIFIER.

Application filed May 28, 1927. Serial No. 194,982.

This invention relates to improvements in water purifiers, and especially to that type in which an electric current is passed thru the water by positioning electrodes in a circuit in such a manner that when they are immersed in the water and the electric energy applied, the electric current passes from one electrode to the other thru the water.

One of the objects of this invention is to produce a water purifier having electrodes that are provided with means for adjusting them toward and from each other.

A further object is to provide a water purifier having conical electrodes in axial alignment.

Other objects of this invention are to render the parts accessible, adjustable and removable for any purpose, as well as to provide for their enclosure and protection while in operation. It is also an object of the instant invention to secure ruggedness, durability and simplicity of construction.

The features of this device will be better understood by referring to the accompanying drawing, wherein

Figure 1, is an elevation of a water cooler immersed in a vessel of water, and embodying this invention.

Fig. 2, is an enlarged longitudinal section of the same, taken on line II-II of Fig. 1.

Fig. 3, is a cross-section taken on line III-III of Fig. 2, with parts removed for clearness.

Fig. 4, is a fragmentary section taken on line IV-IV of Fig. 2.

Fig. 5, is a fragmentary elevation of a modified form of this invention, and

Fig. 6, is a fragmentary elevation showing a further modified form of this invention.

Similar reference characters refer to like parts thruout the several views, and the numeral 7 designates a longitudinally divided handle, composed of similar handle members 8, adapted to be fitted together in such a manner as to form a suitable handle. Handle members 8 are each provided with an off-set portion 9, which are so positioned as to provide suitable supporting means for two electrodes in axial alignment. In off-set portions 9 of handle members 8 are recesses 10 which open outwardly and are provided with internal threads at their outer portion for engaging the threads of cap nuts 12.

Extending from recesses 10 and passing thru the handle members 8 are holes 13 which are suitable for receiving insulated conducting wires 14.

Electrodes 15, which are shown to be of 60 slightly conical shape, and having threaded axial stems 16, are carried by handle members 8 on the inner surfaces of the off-set portions 9 by means of threaded stems 16, which pass thru holes 17 in handle members 65 8, and extend into the recesses 10. For securing said electrodes 15 and handle members 8 in fixed relative position, cap nuts 18 are provided to engage threaded stems 16. The electrodes 15 may be made of any 70 suitable material, and are provided with insulators 19 to insure the passage of the electric current from one electrode to the other thru the water, when the device is in the operative position as shown in Fig. 1. 75 The threaded stems 16 are also insulated from the handle members 8 by insulated packing 20, which is made of very resilient material, such as gum rubber or the like, which permits of considerable compression 80 without destroying its usefulness.

Cap nuts 12 are provided with terminal screws 21 which are adapted to securely hold the wires 14 in contact position. Fitted within the cap nuts 18 are insulating blocks 85 22 which serve as abutments for holding the electrodes 15 in their proper relative positions. Also interposed between said cap nuts 18 and handle members 8, are gaskets 23.

The portions of the insulated wires 14 contained within handle members 8 are protected from the water by means of packings 20, caps 12 and stuffing boxes 24.

In order to be better able to properly position handle members 8, when it is desired to assemble the same, dowel pins 25 have been provided, which are securely attached to one of said handle members 8 and adapted to engage recesses formed in the other 100 handle member 8. When handle members 8 are assembled, they form a cylindrical handle, the outer end of which is provided with a threaded portion 26, which is adapted to receive a threaded ferrule 27, and said handle is also provided with an annular groove 28, adjacent the off-set portions 9 of said handle members 8. Surrounding the off-set portions 9 of handle members 8, and adapted to engage said recesses 28 is a perforated 105 110

split housing, consisting of parts 29 and 30. Handle members 8 and housing parts 29 and 30 are removably held in operative position by means of slip ferrule 31. Housing parts 5 29 and 30 are also positioned at their outer extremity by any suitable fastening means, as shown at 32, in Fig. 2.

Encircling electrodes 15 and integral with handle members 8, are annular flanges 33, 10 the function of which will be hereinafter fully set forth.

In Fig. 5, which shows a modified form of this invention, the perforated housing parts 29' and 30', are shown as integral parts of 15 handle members 8 respectively, while in the modified form as shown in Fig. 6, the housing is made of a single resilient piece of metal formed to the shape of the segment of a circle, and adapted to engage the annular flanges 33 of the handle members 8, is 20 shown.

When it is desired to disassemble the device, threaded ferrule 27 is first removed, then slip ferrule 31 is slipped from its 25 position and over the handle members 8. Housing members 29 and 30 may then be swung out of engagement with the annular groove 28 in handle members 8, and handle members 8 may then be disconnected and 30 free access had to the electrodes 15, and other parts of the device.

To adjust the electrodes 15 toward and from each other, the cap nut 18 is first removed, then the cap nut 12 may be adjusted on the threaded stem 16 of electrodes 15 by which means the distance between the 35 inner surface of said electrode 15 and the head of terminal screw 21 may be varied. Due to the resiliency of insulating packing 40 20, against which cap nut 18 is abutted, the electrode will be held in its extreme outer position until the cap nut 18 is screwed into its seated position, when it will force said electrode 15 to a predetermined position, 45 which is dependent upon the relative positions of lock nut 18 and electrode 15. It is apparent that this axial adjusting may be made on either or both of said electrodes 15.

50 Having thus described the invention what

is claimed as new and desired to be secured by Letters Patent is:

1. In a device of the character described, two electrodes, a longitudinally divided handle carrying the same, means carried by 55 said handle to move said electrodes toward and from each other, a perforated housing enclosing said electrodes and means for removably securing together the members of said divided handle and said housing. 60

2. In a device of the character described, two conical electrodes positioned in axial alignment, a longitudinally divided handle carrying the same, means carried by said handle for moving said electrodes toward 65 and from each other, a perforated housing enclosing said electrodes and removable means securing said divided handle members and housing in fixed relation.

3. In a device of the character described, 70 two axially aligned oppositely disposed convex electrodes, a handle carrying the same and means carried by said handle to move said electrodes toward and from each other.

4. In a device of the character described, 75 a plurality of electrodes in axial alignment, a longitudinally divided handle carrying the same, means carried by said handle for moving said electrodes toward and from each other, hermetically sealed passage-ways extending thru said divided handle to receive electric conductors extending from the electrodes to the opposite end of the handle and means removably securing said divided handle in an operative position. 80

5. In a device of the character described, two conical electrodes positioned in axial alignment, a longitudinally divided handle carrying the same, means carried by said handle to move said electrodes toward and 85 from each other, passage-ways extending thru said handle, electric conductors extending from the electrodes to the opposite end of the handle thru each passage, a perforated housing covering said electrodes and 90 means for removably securing said divided handle and housing in fixed relation. 95

In testimony whereof, I hereunto affix my signature.

WILLIAM M. MYERS.
